STOCKING AND METHOD OF KNITTING
SAMEWoldemar Heinitz, Chemnitz, Germany, assignor
to Schubert & Salzer Maschinenfabrik Aktien-
gesellschaft, Chemnitz, GermanyApplication December 6, 1932, Serial No. 646,002
In Germany December 10, 1931

2 Claims. (Cl. 66—167)

The present invention relates to a method of making stockings in a single operation on flat knitting machines according to which method after finishing the leg part the heel parts are made simultaneously with the foot part connecting them by narrowing enlarged beginning starting courses.

The main object of the invention is to provide a method for obtaining a stocking of such kind having a particularly well fitting heel rounding.

The heel rounding according to the invention is thereby obtained that after finishing the leg part the first row of loops of the heel parts is enlarged, and prior to the narrowing of these rows, selavage loops adapted to be sewed in are formed by widening in some further courses.

In a well known manner, for instance, as described in my United States application Serial Number 488,165, the loops, except the selavage loops, of some rows of loops are transferred in connection with the particularly enlarged rows of loops without narrowing the fabric. Instead of transferring loops in some rows plain rows of loops may, of course, also be formed. In both cases the known narrowing follows which includes narrowing of the selavage loops. In this operation, the narrowing finger is returned for a number of needles less than has been narrowed so that the known narrowing line running at an angle to the wale is obtained.

In the drawings affixed to the specification and forming part thereof, a portion of a fabric knitted according to my method, and the heel portion of two stockings obtained by such knitting, are illustrated diagrammatically by way of example.

In the drawings

Fig. 1 shows, on a magnified scale, the loops at the right of a heel portion, it being understood that the heel portion is exactly similar at the left.

Fig. 2 shows the heel portion of a stocking whose narrowing lines are partly on a wale, and partly at an angle to the wales, and

Fig. 3 shows the heel portion of a stocking whose narrowing lines are exclusively at an angle to the wales.

After finishing the leg part to the row of loops $a-a$ at uniform width to the wale x further knitting is effected to line $b-b$ in rows enlarged to the wale y . The enlarged parts may be formed separately from the middle part of the foot, or the first course, or all courses of these parts may be connected to the foot part. They are required only for the subsequent looping and are looped before the stocking is finished. In the row of loops behind the line $b-b$ the heel rounding according to the invention begins by adding as far as the line $c-c$ a number of widened selavage loops adapted to be sewed in, whereby the en-

larged part $x-y$ obtains the desired width to the wale z which is necessary for the heel rounding.

In the rows of loops from line $c-c$ to line $d-d$ the loops, except the selavage loops, may be transferred without narrowing the fabric, or plain rows of loops are formed from line $c-c$ to line $d-d$.

From line $d-d$ to line $e-e$ the rows of loops including the selavage loops are narrowed in the usual manner by returning the narrowing finger for a lesser number of needles than has been narrowed. In this manner, the known narrowing line extending at an angle to the rows of loops as illustrated in Fig. 2 is obtained. The portion $C-D$ of the narrowing line between the courses $c-c$ and $d-d$ in which the loops were transferred without narrowing, as described, extends on a single wale, while the portion $D-E$ of the narrowing line between the courses $d-d$ and $e-e$ which were narrowed in the usual manner, extends at an angle to the courses.

Plain courses may be knitted between the courses $c-c$ and $d-d$ instead of transferring as described, and in this case a narrowing line is not formed between the courses $c-c$ and $d-d$ as shown in Fig. 3, while the narrowing line $D-E$ from course $d-d$ to course $e-e$ extend at an angle to the wales.

Various changes may be made in the details disclosed in the foregoing specification without departing from the invention or sacrificing the advantages thereof.

In the claims affixed to this specification no selection of any particular modification of the invention is intended to the exclusion of other modifications thereof and the right to subsequently make claim to any modification not covered by these claims is expressly reserved.

I claim:—

1. A method of making a stocking in a single operation on a flat knitting machine, comprising in combination the steps of forming, after finishing the leg portion, enlarged starting courses to obtain part of the heel width, widening of some following courses to obtain the heel rounding by forming selavage loops adapted to be sewed in, knitting several plain courses and subsequently narrowing the fabric.

2. A method of making a stocking in a single operation on a flat knitting machine, comprising in combination the steps of forming, after finishing the leg portion, enlarged starting courses to obtain part of the heel width, widening of some following courses to obtain the heel rounding by forming selavage loops adapted to be sewed in, knitting several courses in which narrowing is effected without transferring the selavage loops and subsequently narrowing the fabric with transfer of the selavage loops.

WOLDEMAR HEINITZ. 60
